Elizabeth N. Graham, New York, N. Y.

Application March 30, 1945, Serial No. 118,785

Term of patent 14 years

(Cl. D20—4)

To all whom it may concern:

Be it known that I, Elizabeth N. Graham, a citizen of the United States of America, residing in New York city, county of New York, and State of New York, have invented a new, original, and ornamental Design for a Brassière, of which the following is a specification, reference being had to the accompanying drawing, forming part thereof, wherein,

I claim:

The ornamental design for a brassière, substantially as shown.

ELIZABETH N. GRAHAM.
